(57) **CLAIM**

The ornamental design for wearable tool holder, as shown and described.

DESCRIPTION

FIG. 1 is a perspective view of a wearable tool holder in accordance with the present invention;

FIG. 2 is a front view thereof;

FIG. 3 is a left side view thereof;

FIG. 4 is a right side view thereof;

FIG. 5 is a rear side view thereof; and,

FIG. 6 is a bottom view thereof.

The broken lines shown in the various Figures are shown for illustrative purposes only and form no part of the claimed design.
